DESIGN FOR A BIRD CAGE OR SIMILAR ARTICLE

Frederick Steinberg, Bronx, N. Y.

Application November 26, 1938, Serial No. 81,407

Term of patent 3½ years

To all whom it may concern:

Be it known that I, Frederick Steinberg, a citizen of the United States, residing in the Bronx, in the county of Bronx and in the State of New York, have invented a new, original, and ornamental Design for a Bird Cage or Similar Article, of which the following is a specification, reference being had to the accompanying drawing forming a part thereof.

Figure 1 is a perspective view of a bird cage showing my new design.

Figure 2 is a sectional view taken on the line 2—2 of Figure 1.

The dominant feature of the present design resides in the underslung seed catching portion of the cage.

I claim:

The ornamental design for a bird cage or similar article, substantially as shown and described.

FREDERICK STEINBERG.
